ELECTRIC DISCHARGE LAMP

Robert Leonard Breadner, Kenton, Henry Grainger Jenkins, Pinner, and Charles Henry Simms, Twickenham, England, assignors to General Electric Company, a corporation of New York

Application February 25, 1946, Serial No. 650,067
In Great Britain December 21, 1944

Section 1, Public Law 690, August 8, 1946
Patent expires December 21, 1964

11 Claims. (Cl. 176—122)

1

The present invention relates to electric discharge lamps having long positive-column discharge paths. The invention is applicable both to cold cathode lamps of the kind usually operated from high voltage and also to hot cathode lamps of the kind frequently operated from ordinary supply voltages. The invention is therefore applicable to hot cathode lamps having their envelopes coated internally with fluorescent powder, in which the discharge passes through mercury vapour usually admixed with a few millimetres pressure of a rare gas such as argon. Such lamps are now of great importance as light sources.

The dimensions of these fluorescent lamps, which are usually but not necessarily of circular cross-section, may vary, for example, from a few inches to several feet in length and from $\frac{1}{2}$ " to 2" in mean diameter. They are usually made by mass production methods and are, therefore, generally straight lengths of tubing. Other shapes, such as grids, spirals, etc., have often been proposed but such shapes do not lend themselves readily to mass production methods and can be obtained, in general, only by manipulation by skilled craftsmen. The operation becomes progressively more difficult to perform as the diameter of the tubing is increased, and as the radius of curvature is decreased.

The simple straight tube has several practical disadvantages. As it may be several feet in length, it obviously requires considerable care in handling to avoid mechanical breakage.

Furthermore, since the electrodes are situated at opposite ends of the tube, a straight tube will require two widely separated external contacts or caps which may need to be very accurately spaced apart to fit into a housing with pre-set sockets for the supply of electric power. Also large linear sources are difficult to deal with optically and where a fitting is used this is large and costly in relation to the wattage of the lamp. For these reasons fluorescent lamps have been virtually ruled out for street lighting where the excellent spectral characteristics of their light might be used to great advantage.

The invention is concerned with discharge lamps of the type in which compactness is secured by giving the discharge path between two electrodes a spiral or like shape and in which the discharge path is a channel formed between two vitreous components sealed together, one or both of the components having one or more up-standing ridges which separate adjacent parts of the discharge path from one another.

2

According to the present invention a discharge lamp of the type specified has a discharge path in the form of a two-start spiral or helix. The electrodes may be arranged in the extremities of the discharge path which are adjacent to one another but preferably they are accommodated in tubulations sealed to the extremities of the discharge path.

In any case by giving the discharge path the form of a two-start spiral, the electrodes and means for making electrical connection therewith can readily be located clear of the lamp surface through which the greater part of the light emission takes place. Two such two-start spiral discharge paths may be provided with the turns of the spirals interleaved with one another and each discharge path may be provided with a different gas or vapour filling and/or different fluorescent coatings whereby a desired colour combination can be obtained.

The invention will be described with reference to the accompanying drawing wherein Fig. 1 shows somewhat diagrammatically one form of discharge passage according to the invention; Fig. 2 is a side view in section along the line 2—2 of Fig. 1; and Fig. 3 is a somewhat diagrammatic plan view of a modification.

In Figs. 1 and 2 of the drawing one spiral discharge passage runs from 10 to the centre and the other from the centre to 11. These passages are bounded by two spiral ridges 12 and 13 interleaved with one another. The ridges 12 and 13 may be formed by moulding, pressing or by the application of a strip or the like of glass to a flat glass disc 18 and fusing the strip to the disc by heating. The outer ends of the ridges are turned inwards at 14 and 15 and joined to the adjacent ridge in order to close the passages. The ridges may be provided on both of the components or one component may be as shown in Fig. 1 of the drawing and a plain glass disc 19 (Fig. 2) may constitute the second component. In any case the components are fused together along the crests of the ridges and in this way a two-start spiral passage closed excepting for the two ends is provided. At the two ends of the passage tubulations 16 and 17 are preferably sealed through one component 18, electrodes 20 and 21 are arranged on pinches 22 in these tubulations, the inner wall surfaces of the passage are if desired coated with fluorescent powder 23, the passage is evacuated, and filled with a suitable gas or vapour and sealed off.

It will be seen that with the form of discharge passage described the electrodes and the means

for making electrical connection therewith can be located outside the greater part of the surface through which light is emitted. With a single start spiral, on the other hand, an electrode is required at or near the centre of the lamp or alternatively a tubulation connected with the central region of the lamp must be provided.

Instead of locating the tubulations 16 and 17 as shown they may be arranged alongside of one another, or at diametrically opposite points or in any other convenient position.

An envelope constructed in the form above described may be made to provide two independent discharge paths each having the form of a two-start spiral or helix and the two paths being sealed from one another and provided with a different gas filling or luminescent powder or both and independent pairs of electrodes; this construction involves suitably modifying the shape of the channels produced in one or both components. In one example of a lamp with two discharge paths, both contain a filling of neon and in one fluorescent zinc silicate may be used as the luminescent powder whilst in the other the luminescent powder may be calcium tungstate as described in British patent specification No. 457,486. The neon with the zinc silicate gives a yellow light and the neon with calcium tungstate a pink light, the mixed light from the combination being a very warm white colour. Alternatively either of the above discharge paths may be used in combination with a discharge path having a mercury vapour filling and using a suitable fluorescent powder such as a mixture of zinc beryllium silicate and magnesium tungstate for example. Such a structure is shown in Fig. 3 wherein electrodes 24, 25 are located at the ends of a discharge path 26, while electrodes 27, 28 are located at the ends of another discharge path 29.

We claim:

1. An electric discharge lamp comprising a glass bulb having a pair of spaced and opposed glass disc-shaped walls separated by a pair of transverse parallel interleaved spiraled glass partitions joined to and between said walls and extending from outer peripheral extremities to a point at the center of the disc-shaped walls where their inner extremities terminate in adjacent spaced relationship whereby to jointly define a continuous spiral passage bounded by the adjacent convolutions of said partitions and extending from the outer extremity thereof to the inner extremities and thence back to another point at the outer extremity, an ionizable medium in said passage, and electrodes arranged at the outer ends only of said passage.

2. An electric discharge lamp comprising a glass bulb having a pair of spaced and opposed glass disc-shaped walls separated by a pair of transverse parallel interleaved spiraled glass partitions joined to and between said walls and extending from outer peripheral extremities to a point at the center of the disc-shaped walls where their inner extremities terminate in adjacent spaced relationship whereby to jointly define a continuous spiral passage bounded by the adjacent convolutions of said partitions and extending from the outer extremity thereof to the inner extremities and thence back to another point at the outer extremity, an ionizable medium in said passage, tubes sealed to the ends only of said passage, and an electrode in each of said tubes.

3. An electric discharge lamp comprising a glass bulb having a pair of spaced and opposed

glass disc-shaped walls separated by two pairs of transverse parallel interleaved spiraled glass partitions joined to and between said walls and each extending from outer peripheral extremities to a point at the center of the disc-shaped walls where their inner extremities terminate in adjacent spaced relationship whereby to jointly define a continuous spiral passage bounded by the adjacent convolutions of said partitions and extending from the outer extremity thereof to the inner extremities and thence back to another point at the outer extremity, an ionizable medium in each of said passages, and electrodes arranged at the outer ends only of each of said

15 4. An electric discharge lamp comprising a glass bulb having a pair of spaced and opposed glass disc-shaped walls separated by two pairs of transverse parallel interleaved spiraled glass partitions joined to and between said walls and each extending from outer peripheral extremities to a point at the center of the disc-shaped walls where their inner extremities terminate in adjacent spaced relationship whereby to jointly define a continuous spiral passage bounded by the adjacent convolutions of said partitions and extending from the outer extremity thereof to the inner extremities and thence back to another point at the outer extremity, an ionizable medium in each of said passages, and electrodes arranged at the outer ends only of each of said

20 5. An electric discharge lamp comprising a glass bulb having a pair of spaced and opposed glass disc-shaped walls separated by a pair of transverse parallel interleaved spiraled glass partitions joined to and between said walls and extending from outer peripheral extremities to a point at the center of the disc-shaped walls where their inner extremities terminate in adjacent spaced relationship whereby to jointly define a continuous spiral passage bounded by the adjacent convolutions of said partitions and extending from the outer extremity thereof to the inner extremities and thence back to another point at the outer extremity, an ionizable medium in each of said passages, and electrodes arranged at the outer ends only of each of said

25 6. An electric discharge lamp comprising a glass bulb having a pair of spaced and opposed glass disc-shaped walls separated by two pairs of transverse parallel interleaved spiraled glass partitions joined to and between said walls and each extending from outer peripheral extremities to a point at the center of the disc-shaped walls where their inner extremities terminate in adjacent spaced relationship whereby to jointly define a continuous spiral passage bounded by the adjacent convolutions of said partitions and extending from the outer extremity thereof to the inner extremities and thence back to another point at the outer extremity, an ionizable medium in each of said passages, fluorescent material on the inside of the walls of said passage, and electrodes arranged at the outer ends only of said passage.

30 7. An electric discharge lamp comprising a glass bulb having a pair of spaced and opposed glass disc-shaped walls separated by two pairs of transverse parallel interleaved spiraled glass partitions joined to and between said walls and each extending from outer peripheral extremities to a point at the center of the disc-shaped walls where their inner extremities terminate in adjacent spaced

relationship whereby to jointly define a continuous spiral passage bounded by the adjacent convolutions of said partitions and extending from the outer extremity thereof to the inner extremities and thence back to another point at the outer extremity, a different ionizable medium in each of said passages, a fluorescent material on the inside wall of at least one of said passages, and electrodes arranged at the outer ends only of each of said passages.

8. An electric discharge lamp comprising a glass bulb having a pair of spaced and opposed glass disc-shaped walls separated by two pairs of transverse parallel interleaved spiraled glass partitions joined to and between said walls and each extending from outer peripheral extremities to a point at the center of the disc-shaped walls where their inner extremities terminate in adjacent spaced relationship whereby to jointly define a continuous spiral passage bounded by the adjacent convolutions of said partitions and extending from the outer extremity thereof to the inner extremities and thence back to another point at the outer extremity, a different ionizable medium in each of said passages, a different fluorescent material in each of said passages, and electrodes arranged at the outer ends only of each of said passages.

9. An electric lamp comprising a sealed flat bulb having a substantially flat bottom wall and a substantially flat transparent cover plate parallel to the bottom wall, convolute partitions in said bulb dividing the same into a plurality of spiral passages each extending from substantially the center to the periphery of the bulb and separated from each other by a single wall extending from the bottom wall to the cover plate and fixedly attached therebetween to maintain the same rigidly within the bulb without sealing the passages from each other, a fluorescent coating on the inner wall surfaces of the passages, thermionic electrodes mounted in the bulb at the peripheral ends only of said passages, lead-ins for the electrodes, and a suitable gas filling said bulb and providing a discharge path between opposing electrodes serving as a source of illumination.

10. An electric discharge lamp comprising a glass bulb having a pair of spaced and opposed walls and a pair of transverse parallel interleaved spiraled partitions between said walls extending from outer extremities to a point where their inner extremities terminate in adjacent spaced relationship whereby to provide a continuous spiral passage bounded by the adjacent convolutions of said partitions and extending from the outer extremity thereof to the inner extremities

and thence back to another point at the outer extremity, the outer end of each of said partitions being turned inward and joined to an adjacent portion of the other partition so that the outermost convolutions of the partitions themselves constitute the outer boundaries of said passage, an ionizable medium in said passage, and electrodes arranged at the outer ends of said passage.

11. An electric discharge lamp comprising a glass bulb having a pair of spaced and opposed glass disc-shaped walls separated by a pair of transverse parallel interleaved spiraled glass partitions joined to and between said walls and extending from outer peripheral extremities to a point at the center of the disc-shaped walls where their inner extremities terminate in adjacent spaced relationship whereby to jointly define a continuous spiral passage bounded by the adjacent convolutions of said partitions and extending from the outer extremity thereof to the inner extremities and thence back to another point at the outer extremity, the outer end of each of said partitions being turned inward and joined to an adjacent portion of the other partition so that the outermost convolutions of the partitions themselves constitute the outer boundaries of said passage, an ionizable medium in said passage, and electrodes arranged at the outer ends only of said passage.
